BENJAMIN F. LEWIS, OF PITTSBURGH, PENNSYLVANIA, ASSIGNOR OF ONE-HALF TO
JOSEPH P. LARKIN, OF PITTSBURGH, PENNSYLVANIA.

TICKET-RECORDING DEVICE.

1,163,422.

Specification of Letters Patent.

Patented Dec. 7, 1915.

Application filed April 24, 1915. Serial No. 23,581.

To all whom it may concern:

Be it known that I, BENJAMIN F. LEWIS, a citizen of the United States, residing at Pittsburgh, in the county of Allegheny and State of Pennsylvania, have invented a new and useful Improvement in Ticket-Recording Devices, of which the following is a full, clear, and exact description, reference being had to the accompanying drawings, forming part of this specification, in which—

Figure 1 is an irregular section through the casing on line I—I of Fig. 2. Fig. 2 is a sectional view on the line II—II of Fig. 1. Fig. 3 is a perspective view of a punch operating device. Figs. 4 and 5 are sectional views on the lines IV—IV and V—V, respectively, of Fig. 1. Fig. 6 is a plan view of the left hand portion of the structure shown in Fig. 1. Fig. 7 is a perspective view of the locking bar. Fig. 8 is a sectional view of the locking bar shown in Fig. 7. Figs. 9 and 10 are detail views of the locking bar operating cam, and Fig. 11 is a plan view of the punch plate.

This invention relates to an improvement in ticket recording devices and is designed to provide a cheap and efficient device for issuing tickets and making a duplicate record of the ticket issued.

The object of my invention is to provide a device of this character in which the feeding device for the main ticket and the duplicate is operated by the duplicate strip, and which is so arranged that after a predetermined length of ticket has been measured off by the feeding device, the feeding device, together with all the mechanism, will be automatically locked to prevent further feeding of the duplicate or main ticket strip, until released for the issuing of another ticket.

The precise nature of my invention will be best understood by reference to the accompanying drawings which will now be described, it being premised, however, that various changes may be made in the details of construction and general arrangement of the parts without departing from the spirit and scope of my invention, as defined in the appended claims.

Referring to the accompanying drawings the numeral 2 designates the casing which may be of any approved type and provided with suitable hinged covers to permit ready access to the working parts, which covers

may be secured in any desired manner to prevent tampering with the mechanism within the casing.

Rotatably mounted on stationary spindles within the casing is a spool 3 containing a strip of duplicate tickets, and a spool 4 containing a strip of original tickets.

5 is a spool connected to a spindle 6 which is rotatably mounted in bearings in the casing, and 7 is a knurled head secured on the outer end of the spindle 6 on the exterior of the casing. The duplicate strip of tickets 8 passes from the spool 3 over a punch plate 9 to the spool 5 and is arranged to be drawn from the spool 3 by the rotation of the spool 5.

Rotatably mounted below the punch plate 9 and in bearings in the casing 2 is a shaft 10, having secured thereto a plurality of perforating wheels 11, which are provided with sharp teeth adapted to pass through the duplicate strip of tickets 8 and the main strip of tickets 12, passing between the punch plate 9 and the cover plate 13 above the punch plate. Connected to the shaft 10 is a stop disk 14 having a cam 15 on one side thereof and a slot 16 in its periphery.

Slidably mounted in guides in the frame is a locking bar 17, the upper face thereof having a recess 18 for the reception of the stop disk 14 and a recess 19 in the lower face thereof for actuating the locking mechanism, as hereinafter described. Connected to the shaft 6 is a ratchet wheel 20 and coacting therewith is a spring pawl 21 to prevent the shaft 6 from being turned in the reverse direction.

22 is a second ratchet wheel connected to the shaft 6, which is engaged by means of a projection 23 on one end of a lever 24 pivoted to the frame of the machine, the other end of the lever 24 extending below the locking bar 17, and is provided with a projection 23^a. When the locking bar 17 is moved outwardly, as shown in dotted lines in Fig. 2, the end of this lever rests in the slot 19 in the bottom of the locking bar and permits the hook 23 to engage the teeth of the ratchet wheel 22 and the projection 23^a to enter the slot 16 in the cam disk, to lock the shafts 6 and 10 from rotation.

25 is a gear wheel on the shaft 10, which meshes with the gear wheel 26 on the shaft of a dating device 27 above the strip of the tickets 12, and which contacts with an inking roller 28, the arrangement being such

that when the tickets are fed forwardly the dating stamp will be rotated to print the date on the main ticket.

Slidably mounted between the top plate 13 and the auxiliary plate 29 are a plurality of punches 30 which are held in their upward position by means of springs 31 surrounding the punches. The punch plate 9 is provided with a plurality of openings 10 which register with the punches 30, so that when either of the punches are moved downwardly the original and duplicate tickets will be simultaneously punched.

In order to avoid the punches being accidentally operated, I have so arranged the punches and their guides that the tops of the punches are slightly below the outer face of the auxiliary top plate 29 and the conductor is provided with an operating device 32 having a projection 33, as shown in Fig. 3, with which he can manipulate any one of the punches, the projection 33 being of such a length that it would be impossible to move the punches out of their guiding openings 28 in the auxiliary cover 29.

The operation of the device is as follows: The duplicate strip ticket is placed on the spool 3 and the end secured to the spool 5 and properly lined up so that the end of one of the tickets will be in proper relation with the punches and an opening 34 through the top of the casing. The main ticket strip 12 is then placed in position over the duplicate strip, the end thereof passing out through the opening 34. Assuming the parts to be free to rotate, as shown in Figs. 1 and 2, the spindle 6 is rotated by means of its head 7 which will wind up the duplicate ticket on the spool 5 and feed out the main ticket through the opening 34. This movement of the duplicate ticket will rotate the shaft 10 through the medium of the perforating wheels 11 which will in turn feed an equal length of original and duplicate tickets. After the shaft 10 has made one revolution, the locking bar 17 will be moved outwardly to its dotted line position in Fig. 2, by means of the cam 15. This outward movement of the locking bar 17 will bring the cut away portion 19 in the under face thereof over the lever 24, which will drop therein and permit the projections 23 and 23^a to move into position to lock the shafts 6 and 10 from further rotation. Of course it will be understood that when the parts are brought into their locked position, the end of the original ticket will be at the edge of the opening 34, which can be torn off. When it is desired to issue another ticket, the locking bar 17 is moved inwardly to its full line position which will actuate the lever 24 and release the mechanism, and permit the shaft 10 to make one revolution when the spindle 6 is rotated, thereby actuating 60 the locking mechanism, as above described.

It will be understood that when the length of the ticket is changed, the size of the perforating wheels will be changed accordingly, as each rotation of the shaft 10 will feed out one original ticket and one duplicate 70 ticket.

The advantages of my invention result from the provision of means for feeding the original ticket by a mechanism actuated by the duplicate strip, together with locking 75 means controlled by the feeding mechanism which is so arranged that only a predetermined length of ticket is fed out by each operation of the machine.

I claim:

1. A ticket recording device, comprising a plurality of spindles for holding strips of original and duplicate tickets, a spindle for receiving the duplicate ticket, means for actuating the last mentioned spindle, and 85 means engaging both tickets and actuated by the duplicate strip of tickets for feeding the main strip of tickets; substantially as described.

2. A ticket recording device, comprising a 90 plurality of spindles for holding strips of original and duplicate tickets, a spindle for receiving the duplicate ticket, means for actuating the last mentioned spindle, means actuated by the duplicate strip of tickets 95 for feeding the main strip of tickets, means for locking the spindle for receiving the strip of duplicate tickets, and means controlled by the feeding device for actuating said lock; substantially as described. 100

3. A ticket recording device, comprising a spool for holding a strip of duplicate tickets, a spool for receiving said tickets, a spool for holding a strip of original tickets and arranged to lie on the upper surface of the 105 strip of duplicate tickets, a guide between which said strips pass, a rotary perforating device below said strips arranged to engage both strips, means for rotating the receiving spool for the duplicate strip, locking means 110 for said spool, and a locking bar actuated by the perforating device; substantially as described.

4. A ticket recording device comprising means for holding a strip of original and a 115 strip of duplicate tickets, means for winding the duplicate strip from the holding means, means actuated by the duplicate strip for feeding the main strip of tickets, and a locking device actuated by the main strip feeding device for locking the mechanism after a predetermined length of original strip has been fed out; substantially as described.

5. A ticket recording device comprising means for holding a strip of original and a 125 strip of duplicate tickets, means for winding the duplicate strip from the holding means, means actuated by the duplicate strip for feeding the main strip of tickets, means for simultaneously punching the original and 130

duplicate strips, and a locking device actuated by the main strip feeding device for locking the mechanism after a predetermined length of original strip has been fed out; substantially as described.

6. A ticket recording device comprising means for holding a strip of original and a strip of duplicate tickets, means for winding the duplicate strip from the holding means, means actuated by the duplicate strip for feeding the main strip of tickets, and a locking device actuated by the main strip feeding device for locking the main strip feeding device and the duplicate strip winder; substantially as described.

7. A ticket recording device, comprising means for holding a duplicate strip of tickets and an original strip of tickets, a winding device for drawing the duplicate strip from its holding device, a feeding device actuated by the duplicate strip for feeding the original strip, a locking lever for locking the winding and feeding devices, and a locking bar actuated by the feeding device for permitting the locking lever to move into locking position; substantially as described.

8. A ticket recording device for issuing original and duplicate tickets, means for holding rolls of original and duplicate tickets, a spindle for receiving the duplicate tickets, means for actuating said spindle, and an original ticket feeding device arranged to pass through the duplicate and original tickets to simultaneously feed both tickets; substantially as described.

9. A ticket recording device for issuing original and duplicate tickets, means for holding rolls of original and duplicate tickets, a spindle for receiving the duplicate tickets, means for actuating said spindle, and an original ticket feeding device arranged to pass through the duplicate and original tickets to simultaneously feed both tickets; together with means for stopping the movement of the feeding device after it has moved a predetermined distance; substantially as described.

In testimony whereof, I have hereunto set my hand.

BENJAMIN F. LEWIS.
